UNITED STATES PATENT OFFICE

2,055,380

STAPLING AND TACKING MACHINE

Augie L. Hansen, Chicago, Ill., assignor to A. L. Hansen Mfg. Co., Chicago, Ill., a corporation of Illinois

Application December 2, 1935, Serial No. 52,493

5 Claims. (Cl. 1—49)

This invention relates to stapling and tacking machines of the kind used for driving wire staples. It relates particularly to the type of stapling machine in which the staples are driven by means of a spring-actuated hammer of the general type shown in Patent No. 1,978,983, issued October 30, 1934, to H. J. Baur.

In stapling machines of the kind, the driving end of the hammer consists of a blade which operates in a way provided by two spaced plates between which the blade reciprocates when driving the staples, which are automatically fed one by one to said way in driving alignment with said blade. These plates are spaced apart by flanges presented by members of the housing containing the guideway for the staples, against which flanges they are held rigidly by means of screws taking through said plates and flanges.

In the operation of a stapling machine of the kind, these plates are subjected to violent vibration and are apt to come loose, with the result that the blade fails to properly drive the staple. The object of the present invention is to provide means for efficiently locking said screws against rotative movement and thus maintaining the two plates providing the way for the driving blade in the required spaced relation.

This and other advantages of the invention will appear more clearly as I proceed with my specification.

In the drawing:—

Figure 1 is a perspective view of a stapling machine of the kind described;

Figure 2 is a front elevation of the outer plate providing the way for the hammer blade, showing the improved lock member engaged with the heads of the screws by which said plate is secured to the arm;

Figure 3 is a rear view of the same with the screws omitted;

Figure 4 is a perspective view of a lock member included in the invention;

Figure 5 is a transverse section through the front end of the hammer carrying arm in a plane indicated by the line 5—5 of Figure 1; and

Figure 6 is a vertical section through Figure 3 in a plane indicated by the line 6—6 of Figure 3.

Referring now to the drawing:—10 indicates the base of the machine; 11 indicates the head at the front end of the base enclosing the familiar spring-controlled plunger which carries the driving blade at its lower end; and 12 indicates the arm for operating the machine.

The driving blade and the spaced plates providing the way through which it operates, are

illustrated in Figure 5. In said figure, 17 and 18 indicate, respectively, the front and back plates at the forward end of the base 10, which plates are secured to opposite faces of inturned flanges 20 at the front end of a channel member 21 extending longitudinally of the base 10. Headed screws 22, 22 taking through the lateral margins of the front plate 17, the flanges 20 and the lateral margins of the back plate 18, clamp the two plates rigidly in position.

These parts are familiar and may be as described in the aforesaid patent and require no further description.

As stated above, the vibration produced in the operation of the hammer, gradually works the screws 22 loose, with the result that the guideway is enlarged and the staple is not always driven properly. To cure this evil, I provide the following construction.

Between the heads 22a of the screws 22 I mount 20 a yoke 23. This yoke, as shown, consists of a substantially rectangular plate through which is cut a T-slot to provide a top bar 24 and depending laterally spaced arms 25, 25.

The yoke is secured to the outer plate 17 by 25 means of a headed screw 26 which is threaded through the plate 17 and has its inner end upset as at 26b in a recess 27 formed at the back of the plate, thus locking the yoke to the plate 17. The head 26a of the screw 26 is conical and 30 is engaged against conical seats 25a on the proximate edges of the depending arms 25 of the yoke. The construction is such that when the screw 26 is screwed inwardly with respect to the plate 17, its conical head 26a will act as a wedge 35 to spread the arms 25 of the yoke apart. The outer edges of the arms 25 are formed to provide jaws 25b for engagement with the rounded head 22a of the screws 22. By spreading apart the yoke 25, the jaws 25b at the outer edges 40 of said arms will be forcibly and frictionally engaged with the heads of said screws, thus locking them against rotative movement.

The construction described rigidly locks the securing screws 22 against rotative movement, 45 with the result that the original width of the way for the hammer blade is maintained.

I claim as my invention:—

1. In a stapling machine, in combination with a driving blade, front and rear spaced plates defining the way of said blade, means for securing said plates in position including headed screws extending through the margins of said plates, a yoke carried by said front plate comprising a top bar and laterally spaced depending arms hav- 55

ing jaws adapted for engagement with the heads of said screws, and a screw threaded into said front plate between said yoke arms and having a conical head, said yoke arms having conical seats at their proximate edges for said conical head.

2. In a stapling machine, in combination with a driving blade, front and rear spaced plates defining the way for said blade, means for securing said plates in position including headed screws extending through the margins of said plates, a yoke carried by said front plate comprising a top bar and laterally spaced depending arms having jaws adapted for engagement with the heads of said screws, a screw threaded into said front plate between said yoke arms and having a conical head, said yoke arms having conical seats at their proximate edges for said conical head, and means for retaining said conical headed screw on said front plate.

3. In a stapling machine, in combination with a driving blade, front and rear spaced plates defining the way for said blade, means for securing said plates in position including headed screws extending through the margins of said plates, a yoke carried by said front plate, said yoke comprising a top bar and laterally spaced

depending arms having jaws adapted for engagement with the heads of said screws, a screw threaded into said front plate between said yoke arms and having its end upset in a recess provided in the rear face of said front plate, said screw having a conical head, and said yoke arms having conical seats at their proximate edges for said conical head.

4. In a stapling machine, in combination with a driving blade, front and rear spaced plates defining the way for said blade, means for securing said plates in position including screws extending through the margins of said plates, an expandible member interposed on said front plate between and engaging said screws, and means for expanding said member.

5. In a stapling machine, in combination with a driving blade, front and rear spaced plates defining the way for said blade, means for securing said plates in position including screws extending through the margins of said plates, an expandible member interposed on said front plate between and engaging said screws, and means for expanding said member including a screw with a conical head, by which said member is secured to said front plate.

AUGIE L. HANSEN.
